Inventor:

John C. DeGnan,
per Thos. S. Crane, Atty.

UNITED STATES PATENT OFFICE.

JOHN C. DEGNAN, OF MIDDLETOWN, NEW YORK.

WATER-MIXER FOR BATHING APPLIANCES.

SPECIFICATION forming part of Letters Patent No. 552,356, dated December 31, 1895.

Application filed March 27 1895. Serial No. 543,329. (No model.)

To all whom it may concern:

Be it known that I, JOHN C. DEGNAN, a citizen of the United States, residing at Middletown, Orange county, New York, have invented certain new and useful Improvements in Water-Mixers for Bathing Appliances, fully described and represented in the following specification and the accompanying drawings, forming a part of the same.

10 The present invention relates to an improved apparatus for use in bathing, and the object of the invention is to furnish an effective means of mingling currents of cold and hot water for delivery to a shower-bath, hand-spray, or douche.

The invention consists of the combination, with an oblong cylindrical mixing-chamber, of two parallel pipes projected within the same from one end and perforated within the 20 chamber and connected, respectively, with hot and cold water supplies outside of the chamber, and a third pipe projecting into the opposite end of the chamber and extended inwardly between the other pipes, such third 25 pipe being open at its inner end to discharge the mixed fluid and connected at its opposite end to a douche.

The invention also includes the construction of the mixing-chamber with two nozzles 30 at one end at opposite sides of the center line, and a nozzle at the opposite end upon the center line, with union-joints formed upon the nozzles and sockets formed upon the inner ends of the nozzles with pipes inserted therein 35 to extend within the chamber, as above described.

The invention will be understood by reference to the annexed drawings, in which—

Figure 1 is a front elevation of the apparatus, with the mixing-chamber and its interior pipes in vertical section. Fig. 2 is a side elevation of the same, and Fig. 3 is a cross-section on line 3 3 in Fig. 2.

40 A designates the mixing-chamber, which is made of an oblong cylinder to permit the extension of the inlet and delivery pipes inside of the same for a considerable distance parallel to one another. The chamber is provided at the bottom with inlet-nozzles B' and C' at opposite sides of the center line, and at 45 the top with an outlet-nozzle D. An outlet-

nozzle G may also, when desired, be formed upon the bottom at the center line, as shown in Fig. 1. The cold-water pipe B² is connected with the nozzle B, and with a cock b by an elbow b'. The hot-water pipe C² is connected with the nozzle C' and with a cock c by an elbow c'. The inner ends of the nozzles are formed with sockets, and pipes B, C and D are inserted in such sockets and projected 55 each nearly to the opposite end of the chamber. The pipes B and C are shown closed at their inner ends by caps and are formed each with numerous perforations e adapted to subdivide the entering-currents and mingle them 60 effectively. The delivery-pipe D is inserted in socket on nozzle D' and extended downward past the perforations or outlets from the pipes B and C, and a pipe D² is extended upward from the nozzle D' and connected with 65 a douche F by a swivel E. The water is delivered from the outlets of the pipes B and C into the middle and upper part of the mixing-chamber and the fluids are forced longitudinally within the chamber in order to enter 70 the end of the discharge-pipe D, so that they are thoroughly mingled before the fluid is discharged. As the mingled fluid is forced to 75 one end of the chamber before it is discharged, another outlet may be taken from such end 80 of the chamber through the nozzle G to a hand-spray g provided with a hand-spray g'. A cock G' is shown coupled to the nozzle G to discharge the mixed fluid to the hand-spray when desired. The oblong cylindrical chamber is 85 shown formed of a cylindrical body with heads applied to the opposite ends, by which construction the sockets may be formed upon the inner ends of the nozzles, and the pipes B, C or D secured in such sockets before the heads 90 are secured upon the cylindrical portion of the chamber.

The construction is exceedingly cheap, simple and effective, and the oblong cylindrical form prevents it from projecting very far from 95 the wall to which it is attached, and which is indicated by a line in Fig. 2, to which the feet of the chamber are applied.

I am aware that it is common to project pipes within the same chamber to mix hot 100 and cold water, and do not claim such a construction broadly.

My construction differs from those heretofore used in the small number and cheapness of the parts.

The chamber A, as shown in Fig. 1 of my drawings, is formed separate from the heads, while the nozzles B', C' and G are formed in one piece with the lower head. The pipes are thus readily connected with the interiors of the heads, while the union-couplings H adapt the mixer for connection with the external pipes in the usual manner.

Having thus set forth the nature of my invention, what I claim herein is—

1. The water mixer herein shown and described, consisting of the oblong cylindrical mixing chamber A provided with the union coupling nozzles B', C' and D', arranged as set forth, and having the three parallel pipes B, C and D projected within the same, and the pipes B and C being perforated upon the sides, and the pipe D being open upon its inner end, as set forth, the hot and cold water pipes connected with the pipes B and C through the nozzles B' and C', and the douche F connected with the pipe D through the nozzle D', the parts being arranged and operated as and for the purpose set forth.

2. The water mixer herein shown and described, consisting of the oblong cylindrical mixing chamber A provided with the union coupling nozzles B', C' and D', having sockets upon their inner ends, the three parallel pipes

B, C and D secured within the said sockets and projected within the chamber, the pipes B and C being provided with numerous water outlets e, and the pipe D being open at its inner end and projected past the water outlets upon the pipes B and C, as set forth, the hot and cold water supply pipes connected by union couplings with the nozzles B' and C', and the douche connected with the nozzle D', the whole arranged and operated as herein set forth.

3. The water mixer herein shown and described, consisting of the oblong cylindrical chamber A, provided with the union coupling nozzles B', C', D' and G, the perforated pipes B and C projected inward from the nozzles B' and C', the pipe D projected inward from the nozzle D' and open upon its inner end, the hot and cold water supply pipes connected with the outer ends of the nozzles B' and C', the douche F connected with the outer end of the nozzle D', and the hand-spray g' having hand-hose g connected with the nozzle G, the whole arranged and operated as and for the purpose set forth.

In testimony whereof I have hereunto set my hand in the presence of two subscribing witnesses.

JOHN C. DEGNAN.
